**COMBINED BARREL HOUSING AND FRAME
FOR A FIREARM**

William B. Ruger, Southport, and Lawrence L. Larson,
Bethany, Conn., assignors to Sturm, Ruger & Co., Inc.,
Southport, Conn., a corporation of Connecticut

Filed Aug. 11, 1969, Ser. No. 18,643

Term of patent 14 years

Int. Cl. D22—02

U.S. Cl. D22—7

FIG. 1**FIG. 2**FIG. 3

FIG. 4

FIG. 1 is a perspective view of the combined barrel housing and frame for a firearm showing our new design.

FIG. 2 is a perspective view of the opposite side thereof.

FIG. 3 is a side elevation thereof.

FIG. 4 is a top plan view thereof.

The firearm trigger and forearm stock are shown in broken lines in FIGS. 1, 2, 3 and 4 for illustrative purposes only.

We claim:

The ornamental design for a combined barrel housing and frame for a firearm, as shown and described.
